ABSTRACT

The innovations disclosed herein concern improvements for a hosted gaming environment to provide improved flexibility, scalability, and game deployment/maintenance. In particular, the multi-form gaming platforms disclosed herein may host so-called “iGaming” sessions (i.e., online gaming with real money wagering), mobile Class-II gaming sessions (e.g., Bingo games) and/or mobile Class-III gaming sessions (e.g., traditional casino-style games), as well as “Social” or “Demo” gaming sessions (i.e., online gaming with non-real money wagering). The innovations disclosed herein have the following technical benefits: (1) the ability for systems to utilize Class-II and Class-III games in real money gaming (“RMG”) and Social gaming; (2) the creation of “Social” versions of Bingo games; (3) reducing the overall number of game builds needed for each separate platform; (4) reusing games in different markets; (5) reducing branches in platform codebases; (6) reducing deployment effort and optimizing support teams; and (7) easing maintenance and upkeep for games across platforms.

MULTI-FORM GAME PLATFORM FOR ONLINE AND SOCIAL GAMING

TECHNICAL FIELD

The present application concerns improvements for a hosted gaming environment to provide improved flexibility, scalability, and game deployment/maintenance. In particular, a hosted gaming platform may be used to provide backend data services—such as the determination of spin results for mobile slot-based games and/or the determination of bingo results for mobile bingo games—to a number of different players and/or for a number of different games, while maintaining a consistent and seamless user experience.

BACKGROUND

Electronic gaming devices, such as electronic gaming machines (EGMs), computers, or other mobile devices, can provide a variety of wagering games such as slot games, video poker games, video blackjack games, roulette games, video bingo games, keno games and other types of games that are frequently offered at casinos and other locations. Play on electronic gaming devices typically involves a player establishing a credit balance by inputting money, or another form of monetary (or non-monetary) credit and placing a monetary (or non-monetary) wager from the credit balance on one or more outcomes of an instance (or single play) of a primary or base game.

“Slot”-type games are often displayed to the player in the form of various symbols arrayed in a row-by-column grid or matrix. Specific matching combinations of symbols along predetermined paths (or paylines) through the matrix indicate the outcome of the game. The display typically highlights winning combinations/outcomes for identification by the player. Matching combinations and their corresponding awards are usually shown in a “pay-table” which is available to the player for reference. Often, the player may vary his/her wager to include differing numbers of paylines and/or the amount bet on each line. By varying the wager, the player may sometimes alter the frequency or number of winning combinations, frequency or number of secondary games, and/or the amount awarded.

Typical casino games use a random number generator (RNG) to randomly determine the outcome of each game. The game is designed to return a certain percentage of the amount wagered back to the player over the course of many plays or instances of the game, which is generally referred to as return to player (RTP). The RTP and randomness of the RNG ensure the fairness of the games and are highly regulated. Upon initiation of play, the RNG randomly determines a game outcome and symbols are then selected which correspond to that outcome. Notably, some games may include an element of skill on the part of the player and are therefore not entirely random.

Slot games and other wagering games may be developed by many different gaming studios, and such games may have many concerns in common, such as updatability, auditability (e.g., from a regulatory standpoint), and data accuracy. Thus, it would be beneficial, from both a game development and user experience standpoint, to provide a novel hosted gaming environment with improved flexibility, scalability, and data security/integrity. In particular, a hosted gaming platform may be used to provide various backend data services, such as the determination of spin results for slot-based games (and/or the determination of other random-based

outcomes for other types of games, such as Bingo games), to a number of different players and/or for a number of different games, while maintaining a consistent and seamless user experience, e.g., a user experience that is able to mimic the responsiveness and “look and feel” of real money gaming (“RMG”) environments in “Social” or “Demo” (i.e., non-real money gaming) environments.

BRIEF DESCRIPTION OF THE DRAWINGS

FIG. 1 is an exemplary diagram showing several EGMs networked with various gaming-related servers.

FIG. 2A is a block diagram showing various functional elements of an exemplary EGM.

FIG. 2B depicts a casino gaming environment according to one example.

FIG. 2C is a diagram that shows examples of components of a system for providing online gaming according to some aspects of the present disclosure.

FIG. 3 illustrates, in block diagram form, an implementation of a game processing architecture algorithm that implements a game processing pipeline for the play of a game, in accordance with various implementations described herein.

FIG. 4 illustrates an exemplary multi-form hosted gaming platform architecture, in accordance with various implementations described herein.

FIG. 5A illustrates an exemplary multi-form hosted gaming platform architecture configuration for mobile Class-II gaming, in accordance with various implementations described herein.

FIG. 5B illustrates an exemplary multi-form hosted gaming platform architecture configuration for mobile Class-III gaming, in accordance with various implementations described herein.

FIG. 6 is a flowchart illustrating an example method for performing an embodiment of the disclosed technology related to executing a flexible, multi-form hosted gaming platform architecture.

FIG. 7 is a process flow diagram illustrating additional details regarding an example method for performing an embodiment of the disclosed technology related to executing a flexible, multi-form hosted gaming platform architecture for a game operating in a “Demo” mode.

DETAILED DESCRIPTION

I. Introduction

I.A. Overview

The disclosed technology is directed to several features of electronic gaming devices and hosted gaming platforms for hosting games to be played on such electronic gaming devices. For example, a hosted gaming platform may involve the use of various components, such as: remote gaming servers, gaming development kit (GDK) game hosts, bingo game managers, outcome resolvers, as well as other integration software to configure what parts of the platform are utilized based on what type of game is being played by the player. These components may be intentionally sandboxed from each other, thereby allowing them to execute without interdependence on one another, and providing game developers the ability to use different version libraries, thereby allowing a more flexible development environment for game developers. In some embodiments, the hosted gaming platform may have an improved technical design, providing such benefits as: (1) the ability for systems to

utilize Class-II and Class-III games in real money gaming (“RMG”) and Social gaming; (2) the creation of “Social” versions of Bingo games; (3) reducing the overall number of game builds needed for each separate platform; (4) reusing games in different markets; (5) reducing branches in platform codebases; (6) reducing deployment effort and optimizing support teams; and (7) easing maintenance and upkeep for games across platforms.

In one example of the various innovations disclosed herein relate to multi-form gaming platforms for online and social gaming. In particular, the innovations disclosed herein relate to so-called “iGaming” (i.e., online gaming with real money wagering), mobile Class-II (“MC2”) gaming (e.g., Bingo games), and so-called “Social” or “Demo” gaming (i.e., online gaming with non-real money wagering). Some of the key features of the multi-form gaming platforms for online and social gaming described herein may include: (1) the ability to use a single remote gaming server (“RGS”) for each of RMG, Social, and Demo (also sometimes referred to as “Free-to-Play”) games; (2) the ability to use Class-II games for social gaming; (3) the ability for a game platform to derive outcomes based on the reel positions (which positions may be derived from the Bingo game for Class-II and from an RNG for Class-III games); (4) the ability to allow game configurations to define the type (e.g., Class-II or Class-III) of game that will be played; and (5) the ability to have a parameter that may be set at the time of game launch to define game mode (e.g., real money gaming mode, Demo mode, Social mode, etc.).

The innovations disclosed herein can be implemented as part of a method, as part of an electronic gaming device, such as an EGM or mobile device, or on an electronic gaming server or other computer server(s) configured to perform the method, or as part of non-transitory computer-readable media storing computer-executable instructions for causing one or more processors in a computer system to perform the method. The various innovations can be used in combination or separately. This summary is provided to introduce a selection of concepts in a simplified form that are further described below in the detailed description. This summary is not intended to identify key features or essential features of the claimed subject matter, nor is it intended to be used to limit the scope of the claimed subject matter. The foregoing and other objects, features, and advantages of the invention will become more apparent from the following detailed description, which proceeds with reference to the accompanying figures and illustrates a number of examples. Examples may also be capable of other and different applications, and some details may be modified in various respects all without departing from the spirit and scope of the disclosed innovations.

I.B. General Considerations.

The detailed description presents innovations in electronic gaming machines (“EGMs”) and other electronic gaming devices and computer-implemented systems. Various alternatives to the examples described herein are possible. For example, some of the methods described herein can be altered by changing the ordering of the method acts described, by splitting, repeating, or omitting certain method acts, etc. The various aspects of the disclosed technology can be used in combination or separately. Some of the innovations described herein address one or more of the problems noted in the background. Typically, a given technique/tool does not solve all such problems. It is to be understood that other examples may be utilized and that structural, logical, software, hardware, and electrical changes may be made without departing from the scope of the disclosure. The

following description is, therefore, not to be taken in a limited sense. Rather, the scope of the present disclosure is defined by the appended claims.

The innovations described herein may, among other things: execute a hosted gaming platform, wherein the hosted gaming platform comprises at least a remote gaming server (RGS), a real money gaming (RMG) infrastructure, and at least one interface to a non-RMG infrastructure; receiving, at the RGS, a first request from a current round of 10 a first gameplay session executing at a frontend gaming client, wherein the first request comprises at least session metadata and an identifier for a first user, wherein the session metadata indicates whether the first gameplay session comprises a RMG session or a non-RMG session. Then, in 15 response to the session metadata indicating that the first gameplay session comprises a RMG session, the platform may execute, using at least the RMG infrastructure, the first request to produce one or more results for the current round. If, instead, the session metadata indicates that the first 20 gameplay session comprises a non-RMG session, the platform may route the first request, via the at least one interface, to the non-RMG infrastructure (which may, e.g., be external to the platform), and receive one or more results for the current round produced by the non-RMG infrastructure, and thereafter return the one or more results for the 25 current round to the frontend gaming client.

In some embodiments, the RGS may be configured to manage one or more user wallets (e.g., RMG wallets and/or non-RMG wallets). In other embodiments, the RGS may be configured to receive information from: one or more external 30 Class-II player account management (PAM) systems and/or one or more external Class-III PAM systems.

In other embodiments, the first gameplay session may comprise at least one of: a Class-II gameplay session; or a 35 Class-III gameplay session. In the case of Class-II gameplay sessions, the one or more results may be produced by utilizing a bingo server. In the case of Class-III gameplay sessions, the one or more results may be produced by utilizing an outcome resolver and a random number generator (RNG).

In still other embodiments, the non-RMG infrastructure may further comprise an infrastructure configured to produce results for social gameplay sessions and/or an infrastructure configured to produce results for demo gameplay sessions.

II. Example Electronic Gaming Servers and Electronic Gaming Machines or Devices

FIG. 1 illustrates several different models of EGMs which may be networked to various gaming related servers. Shown is a system 100 in a gaming environment including one or more server computers 102 (e.g., slot servers of a casino) that are in communication, via a communications network, 55 with one or more gaming devices 104A-104X (EGMs, slots, video poker, bingo machines, etc.), which server computers 102 can implement one or more aspects of the present disclosure. The gaming devices 104A-104X may alternatively be portable and/or remote gaming devices such as, but 60 not limited to, a smart phone, a tablet, a laptop, or a game console. Gaming devices 104A-104X utilize specialized software and/or hardware to form non-generic, particular machines or apparatuses that comply with regulatory requirements regarding devices used for wagering or games of chance that provide monetary awards.

Communication between the gaming devices 104A-104X and the server computers 102, and among the gaming

devices **104A-104X**, may be direct or indirect using one or more communication protocols. As an example, gaming devices **104A-104X** and the server computers **102** can communicate over one or more communication networks, such as over the Internet, through a website maintained by a computer on a remote server, or over an online data network, including commercial online service providers, Internet service providers, private networks (e.g., local area networks and enterprise networks), and the like (e.g., wide area networks). The communication networks could allow gaming devices **104A-104X** to communicate with one another and/or the server computers **102** using a variety of communication-based technologies, such as radio frequency (RF) (e.g., wireless fidelity (WiFi®) and Bluetooth®), cable TV, satellite links and the like.

In some implementations, server computers **102** may not be necessary and/or preferred. For example, in one or more implementations, a stand-alone gaming device such as gaming device **104A**, gaming device **104B** or any of the other gaming devices **104C-104X** can implement one or more aspects of the present disclosure while connected locally to a machine hosting the aforementioned gaming platform. In some such cases, the local machine(s) hosting the gaming platform may be within the gaming device **104**. However, it is typical to find multiple electronic gaming devices connected to networks implemented with one or more of the different server computers **102** described herein.

II.A. Example Server Computers.

The server computers **102** may include an outcome determination server **106**, e.g., a central determination gaming system server, a multimedia content distribution server, or other type of backend server (examples of which will be discussed in greater detail below), a ticket-in-ticket-out (TITO) system server **108**, a player tracking system server **110**, a progressive system server **112**, and/or a casino management system server **114**. Gaming devices **104A-104X** may include features to enable operation of any or all servers for use by the player and/or operator (e.g., the casino, resort, gaming establishment, tavern, pub, etc.). For example, game outcomes may be generated on an outcome determination server **106** and then transmitted over the network to any of a group of remote terminals or remote gaming devices **104A-104X** that utilize the game outcomes and display the results to the players.

II.B. Example Gaming Devices

Gaming device **104A** is often of a cabinet construction which may be aligned in rows or banks of similar devices for placement and operation on a casino floor. The gaming device **104A** often includes a main door which provides access to the interior of the cabinet. Gaming device **104A** typically includes a button area or button deck **120** accessible by a player that is configured with input switches or buttons **122**, an access channel for a bill validator **124**, and/or an access channel for a ticket-out printer **126**.

In FIG. 1, gaming device **104A** is shown as a Relm XL™ model gaming device manufactured by Aristocrat® Technologies, Inc. As shown, gaming device **104A** is a reel machine having a gaming display area **118** comprising a number (typically 3 or 5) of mechanical reels **130** with various symbols displayed on them. The mechanical reels **130** are independently spun and stopped to show a set of symbols within the gaming display area **118** which may be used to determine an outcome to the game.

In many configurations, the gaming device **104A** may have a main display **128** (e.g., video display monitor) mounted to, or above, the gaming display area **118**. The main display **128** can be a high-resolution liquid crystal display

(LCD), plasma, light emitting diode (LED), or organic light emitting diode (OLED) panel which may be flat or curved as shown, a cathode ray tube, or other conventional electronically controlled video monitor.

In some implementations, the bill validator **124** may also function as a “ticket-in” reader that allows the player to use a casino issued credit ticket to load credits onto the gaming device **104A** (e.g., in a cashless ticket (“TITO”) system). In such cashless implementations, the gaming device **104A** may also include a “ticket-out” printer **126** for outputting a credit ticket when a “cash out” button is pressed. Cashless TITO systems are used to generate and track unique bar-codes or other indicators printed on tickets to allow players to avoid the use of bills and coins by loading credits using a ticket reader and cashing out credits using a ticket-out printer **126** on the gaming device **104A**. The gaming device **104A** can have hardware meters for purposes including ensuring regulatory compliance and monitoring the player credit balance. In addition, there can be additional meters that record the total amount of money wagered on the gaming device, total amount of money deposited, total amount of money withdrawn, total amount of winnings on gaming device **104A**.

In some implementations, a player tracking card reader **144**, a transceiver for wireless communication with a mobile device (e.g., a player’s smartphone), a keypad **146**, and/or an illuminated display **148** for reading, receiving, entering, and/or displaying player tracking information is provided in gaming device **104A**. In such implementations, a game controller within the gaming device **104A** can communicate with the player tracking system server **110** to send and receive player tracking information.

Gaming device **104A** may also include a bonus topper wheel **134**. When bonus play is triggered (e.g., by a player achieving a particular outcome or set of outcomes in the primary game), bonus topper wheel **134** is operative to spin and stop with indicator arrow **136** indicating the outcome of the bonus game. Bonus topper wheel **134** is typically used to play a bonus game, but it could also be incorporated into play of the base or primary game.

A candle **138** may be mounted on the top of gaming device **104A** and may be activated by a player (e.g., using a switch or one of buttons **122**) to indicate to operations staff that gaming device **104A** has experienced a malfunction or the player requires service. The candle **138** is also often used to indicate a jackpot has been won and to alert staff that a hand payout of an award may be needed.

There may also be one or more information panels **152** which may be a back-lit, silkscreened glass panel with lettering to indicate general game information including, for example, a game denomination (e.g., \$0.25 or \$1), pay lines, pay tables, and/or various game related graphics. In some implementations, the information panel(s) **152** may be implemented as an additional video display.

Gaming devices **104A** have traditionally also included a handle **132** typically mounted to the side of main cabinet **116** which may be used to initiate game play.

Many or all the above described components can be controlled by circuitry (e.g., a game controller) housed inside the main cabinet **116** of the gaming device **104A**, the details of which are shown in FIG. 2A.

An alternative example gaming device **104B** illustrated in FIG. 1 is the Arc™ model gaming device manufactured by Aristocrat® Technologies, Inc. Note that where possible, reference numerals identifying similar features of the gaming device **104A** implementation are also identified in the gaming device **104B** implementation using the same refer-

ence numbers. Gaming device 104B does not include physical reels and instead shows game play functions on main display 128. An optional topper screen 140 may be used as a secondary game display for bonus play, to show game features or attraction activities while a game is not in play, or any other information or media desired by the game designer or operator. In some implementations, the optional topper screen 140 may also or alternatively be used to display progressive jackpot prizes available to a player during play of gaming device 104B.

Example gaming device 104B includes a main cabinet 116 including a main door which opens to provide access to the interior of the gaming device 104B. The main or service door is typically used by service personnel to refill the ticket-out printer 126 and collect bills and tickets inserted into the bill validator 124. The main or service door may also be accessed to reset the machine, verify and/or upgrade the software, and for general maintenance operations.

Another example gaming device 104C shown is the Helix™ model gaming device manufactured by Aristocrat® Technologies, Inc. Gaming device 104C includes a main display 128A that is in a landscape orientation. Although not illustrated by the front view provided, the main display 128A may have a curvature radius from top to bottom, or alternatively from side to side. In some implementations, main display 128A is a flat panel display. Main display 128A is typically used for primary game play while secondary display 128B is typically used for bonus game play, to show game features or attraction activities while the game is not in play or any other information or media desired by the game designer or operator. In some implementations, example gaming device 104C may also include speakers 142 to output various audio such as game sound, background music, etc.

Many different types of games, including mechanical slot games, video slot games, video poker, video black jack, video pachinko, keno, bingo, and lottery, may be provided with or implemented within the depicted gaming devices 104A-104C and other similar gaming devices. Each gaming device may also be operable to provide many different games. Games may be differentiated according to themes, sounds, graphics, type of game (e.g., slot game vs. card game vs. game with aspects of skill), denomination, number of paylines, maximum jackpot, progressive or non-progressive, bonus games, and may be deployed for operation in Class 2 or Class 3, etc.

II.C. Example Components of Gaming Devices

FIG. 2A is a block diagram depicting exemplary internal electronic components of a gaming device 200 connected to various external systems. All or parts of the gaming device 200 shown could be used to implement any one of the example gaming devices 104A-X depicted in FIG. 1. As shown in FIG. 2A, gaming device 200 includes a topper display 216 or another form of a top box (e.g., a topper wheel, a topper screen, etc.) that sits above cabinet 218. Cabinet 218 or topper display 216 may also house a number of other components which may be used to add features to a game being played on gaming device 200, including speakers 220, a ticket printer 222 which prints bar-coded tickets or other media or mechanisms for storing or indicating a player's credit value, a ticket reader 224 which reads bar-coded tickets or other media or mechanisms for storing or indicating a player's credit value, and a player tracking interface 232. Player tracking interface 232 may include a keypad 226 for entering information, a player tracking display 228 for displaying information (e.g., an illuminated or video display), a card reader 230 for receiving data and/or

communicating information to and from media or a device such as a smart phone enabling player tracking. FIG. 2 also depicts utilizing a ticket printer 222 to print tickets for a TITO system server 108. Gaming device 200 may further include a bill validator 234, player-input buttons 236 for player input, cabinet security sensors 238 to detect unauthorized opening of the cabinet 218, a primary game display 240, and a secondary game display 242, each coupled to and operable under the control of game controller 202.

10 The games available for play on the gaming device 200 are controlled by a game controller 202 that includes one or more processors 204. Processor 204 represents a general-purpose processor, a specialized processor intended to perform certain functional tasks, or a combination thereof. As 15 an example, processor 204 can be a central processing unit (CPU) that has one or more multi-core processing units and memory mediums (e.g., cache memory) that function as buffers and/or temporary storage for data. Alternatively, processor 204 can be a specialized processor, such as an 20 application specific integrated circuit (ASIC), graphics processing unit (GPU), field-programmable gate array (FPGA), digital signal processor (DSP), or another type of hardware accelerator. In another example, processor 204 is a system on chip (SoC) that combines and integrates one or more 25 general-purpose processors and/or one or more specialized processors. Although FIG. 2A illustrates that game controller 202 includes a single processor 204, game controller 202 is not limited to this representation and instead can include multiple processors 204 (e.g., two or more processors).

30 FIG. 2A illustrates that processor 204 is operatively coupled to memory 208. Memory 208 is defined herein as including volatile and nonvolatile memory and other types of non-transitory data storage components. Volatile memory is memory that do not retain data values upon loss of power.

35 Nonvolatile memory is memory that do retain data upon a loss of power. Examples of memory 208 include random access memory (RAM), read-only memory (ROM), hard disk drives, solid-state drives, universal serial bus (USB) flash drives, memory cards accessed via a memory card reader, floppy disks accessed via an associated floppy disk drive, optical discs accessed via an optical disc drive, magnetic tapes accessed via an appropriate tape drive, and/or other memory components, or a combination of any 40 two or more of these memory components. In addition, examples of RAM include static random access memory (SRAM), dynamic random access memory (DRAM), magnetic random access memory (MRAM), and other such devices. Examples of ROM include a programmable read-only memory (PROM), an erasable programmable read-only 45 memory (EPROM), an electrically erasable programmable read-only memory (EEPROM), or other like memory device. Even though FIG. 2A illustrates that game controller 202 includes a single memory 208, game controller 202 could include multiple memories 208 for storing program 50 instructions and/or data.

55 Memory 208 can store one or more game programs 206 that provide program instructions and/or data for carrying out various implementations (e.g., game mechanics) described herein. Stated another way, game program 206 represents an executable program stored in any portion or component of memory 208. In one or more implementations, game program 206 is embodied in the form of source code that includes human-readable statements written in a programming language or machine code that contains 60 numerical instructions recognizable by a suitable execution system, such as a processor 204 in a game controller or other system. Examples of executable programs include: (1) a 65

compiled program that can be translated into machine code in a format that can be loaded into a random access portion of memory 208 and run by processor 204; (2) source code that may be expressed in proper format such as object code that is capable of being loaded into a random access portion of memory 208 and executed by processor 204; and (3) source code that may be interpreted by another executable program to generate instructions in a random access portion of memory 208 to be executed by processor 204.

Alternatively, game programs 206 can be set up to generate one or more game instances based on instructions and/or data that gaming device 200 exchanges with one or more remote gaming devices, such as an outcome determination server 106 (also shown in FIG. 1). For purpose of this disclosure, the term “game instance” refers to a play or a round of a game that gaming device 200 presents (e.g., via a user interface (UI)) to a player. The game instance is communicated to gaming device 200 via the network 214 and then displayed on gaming device 200. For example, gaming device 200 may execute game program 206 as video streaming software that allows the game to be displayed on gaming device 200.

In some embodiments, the outcome determination server 106 may comprise a multi-threaded architecture, allowing multiple connections and/or game instances to utilize the outcome determination server 106. In some implementations, e.g., wherein the outcome determination server 106 is hosted at a cloud service provider, the amount of resources at the cloud service provider that are dedicated to a particular game (e.g., number of servers, number of threads, amount of memory, bandwidth, etc.) may be scaled dynamically to accommodate the real-time needs of the hosted game. When a game is stored on gaming device 200, it may be loaded from memory 208 (e.g., from a read only memory (ROM)) or from the outcome determination server 106 to memory 208.

Gaming devices, such as gaming device 200, are highly regulated to ensure fairness and, in many cases, gaming device 200 is operable to award monetary awards (e.g., typically dispensed in the form of a redeemable voucher). Therefore, to satisfy security and regulatory requirements in a gaming environment, hardware and software architectures are implemented in gaming devices 200 that differ significantly from those of general-purpose computers. Adapting general purpose computers to function as gaming devices 200 is not simple or straightforward because of: (1) the regulatory requirements for gaming devices 200, (2) the harsh environment in which gaming devices 200 operate, (3) security requirements, (4) fault tolerance requirements, and (5) the requirement for additional special purpose components enabling functionality of an EGM. These differences require substantial engineering effort with respect to game design implementation, game mechanics, hardware components, and software.

One regulatory requirement for games running on gaming device 200 generally involves complying with a certain level of randomness. Typically, gaming jurisdictions mandate that gaming devices 200 satisfy a minimum level of randomness without specifying how a gaming device 200 should achieve this level of randomness. To comply, FIG. 2A illustrates that gaming device 200 could include an RNG 212 that utilizes hardware and/or software to generate RNG outcomes that lack any pattern. The RNG operations are often specialized and non-generic in order to comply with regulatory and gaming requirements. For example, in a slot game, game program 206 can initiate multiple RNG calls to RNG 212 to generate RNG outcomes, where each RNG call and RNG

outcome corresponds to an outcome for a reel. In another example, gaming device 200 can be a Class II gaming device where RNG 212 generates RNG outcomes for creating Bingo cards. In one or more implementations, RNG 212 could be one of a set of RNGs operating on gaming device 200. More generally, an output of the RNG 212 can be the basis on which game outcomes are determined by the game controller 202. Game developers could vary the degree of true randomness for each RNG (e.g., pseudorandom) and utilize specific RNGs depending on game requirements. The output of the RNG 212 can include a random number or pseudorandom number (either is generally referred to as a “random number”).

In FIG. 2A, RNG 212 and hardware RNG 244 are shown in dashed lines to illustrate that RNG 212, hardware RNG 244, or both can be included in gaming device 200. In one implementation, instead of including RNG 212, gaming device 200 could include a hardware RNG 244 that generates RNG outcomes. Analogous to RNG 212, hardware RNG 244 performs specialized and non-generic operations in order to comply with regulatory and gaming requirements. For example, because of regulation requirements, hardware RNG 244 could be a random number generator that securely produces random numbers for cryptography use. The gaming device 200 then uses the secure random numbers to generate game outcomes for one or more game features. In another implementation, the gaming device 200 could include both hardware RNG 244 and RNG 212. RNG 212 may utilize the RNG outcomes from hardware RNG 244 as one of many sources of entropy for generating secure random numbers for the game features. It is to be understood that, in certain embodiments, one or more of the functions described above as being performed by game controller 202 (e.g., the RNG functionality, game program storage and/or execution, etc.) may also be performed in whole, or in part, by a hosted server platform, such as outcome determination server 106 or other servers. As will be explained in more detail below, in some embodiments, a client/server architecture may be employed with a game front end application passing requests and other information to a game backend layer, e.g., via an application service layer.

Another regulatory requirement for running games on gaming device 200 includes ensuring a certain level of RTP. Similar to the randomness requirement discussed above, numerous gaming jurisdictions also mandate that gaming device 200 provides a minimum level of RTP (e.g., RTP of at least 75%). A game can use one or more lookup tables (also called weighted tables) as part of a technical solution that satisfies regulatory requirements for randomness and RTP. In particular, a lookup table can integrate game features (e.g., trigger events for special modes or bonus games; newly introduced game elements such as extra reels, new symbols, or new cards; stop positions for dynamic game elements such as spinning reels, spinning wheels, or shifting reels; or card selections from a deck) with random numbers generated by one or more RNGs, so as to achieve a given level of volatility for a target level of RTP. (In general, volatility refers to the frequency or probability of an event such as a special mode, payout, etc. For example, for a target level of RTP, a higher-volatility game may have a lower payout most of the time with an occasional bonus having a very high payout, while a lower-volatility game has a steadier payout with more frequent bonuses of smaller amounts.) Configuring a lookup table can involve engineering decisions with respect to how RNG outcomes are mapped to game outcomes for a given game feature, while still satisfying regulatory requirements for RTP. Configuring

a lookup table can also involve engineering decisions about whether different game features are combined in a given entry of the lookup table or split between different entries (for the respective game features), while still satisfying regulatory requirements for RTP and allowing for varying levels of game volatility.

FIG. 2A illustrates that gaming device 200 includes an RNG conversion engine 210 that translates the RNG outcome from RNG 212 to a game outcome presented to a player. To meet a designated RTP, a game developer can set up the RNG conversion engine 210 to utilize one or more lookup tables to translate the RNG outcome to a symbol element, stop position on a reel strip layout, and/or other randomly chosen aspect of a game feature. As an example, the lookup tables can regulate a prize payout amount for each RNG outcome and how often the gaming device 200 pays out the prize payout amounts. The RNG conversion engine 210 could utilize one lookup table to map the RNG outcome to a game outcome displayed to a player and a second lookup table as a pay table for determining the prize payout amount for each game outcome. The mapping between the RNG outcome to the game outcome controls the frequency in hitting certain prize payout amounts.

FIG. 2A also depicts that gaming device 200 is connected over network 214 to player tracking system server 110. Player tracking system server 110 may be, for example, an OASIS® system manufactured by Aristocrat® Technologies, Inc. Player tracking system server 110 is used to track play (e.g., amount wagered, games played, time of play and/or other quantitative or qualitative measures) for individual players so that an operator may reward players in a loyalty program. The player may use the player tracking interface 232 to access his/her account information, activate free play, and/or request various information. Player tracking or loyalty programs seek to reward players for their play and help build brand loyalty to the gaming establishment. The rewards typically correspond to the player's level of patronage (e.g., to the player's playing frequency and/or total amount of game plays at a given casino). Player tracking rewards may be complimentary and/or discounted meals, lodging, entertainment and/or additional play. Player tracking information may be combined with other information that is now readily obtainable by a casino management system.

When a player wishes to play the gaming device 200, he/she can insert cash or a ticket voucher through a coin acceptor (not shown) or bill validator 234 to establish a credit balance on the gaming device. The credit balance is used by the player to place wagers on instances of the game and to receive credit awards based on the outcome of winning instances. The credit balance is decreased by the amount of each wager and increased upon a win. The player can add additional credits to the balance at any time. The player may also optionally insert a loyalty club card into the card reader 230. During the game, the player views with one or more UIs, the game outcome on one or more of the primary game display 240 and secondary game display 242. Other game and prize information may also be displayed.

For each game instance, a player may make selections, which may affect play of the game. For example, the player may vary the total amount wagered by selecting the amount bet per line and the number of lines played. In many games, the player is asked to initiate or select options during course of game play (such as spinning a wheel to begin a bonus round or select various items during a feature game). The player may make these selections using the player-input buttons 236, the primary game display 240 which may be a

touch screen, or using some other device which enables a player to input information into the gaming device 200.

During certain game events, the gaming device 200 may display visual and auditory effects that can be perceived by the player. These effects add to the excitement of a game, which makes a player more likely to enjoy the playing experience. Auditory effects include various sounds that are projected by the speakers 220. Visual effects include flashing lights, strobing lights or other patterns displayed from lights on the gaming device 200 or from lights behind the information panel 152 (FIG. 1).

When the player is done, he/she cashes out the credit balance (typically by pressing a cash out button to receive a ticket from the ticket printer 222). The ticket may be "cashed-in" for money or inserted into another machine to establish a credit balance for play.

Additionally, or alternatively, gaming devices 104A-104X and 200 can include or be coupled to one or more wireless transmitters, receivers, and/or transceivers (not shown in FIGS. 1 and 2A) that communicate (e.g., Bluetooth® or other near-field communication technology) with one or more mobile devices to perform a variety of wireless operations in a casino environment. Examples of wireless operations in a casino environment include detecting the presence of mobile devices, performing credit, points, comps, or other marketing or hard currency transfers, establishing wagering sessions, and/or providing a personalized casino-based experience using a mobile application. In one implementation, to perform these wireless operations, a wireless transmitter or transceiver initiates a secure wireless connection between a gaming device 104A-104X and 200 and a mobile device. After establishing a secure wireless connection between the gaming device 104A-104X and 200 and the mobile device, the wireless transmitter or transceiver does not send and/or receive application data to and/or from the mobile device. Rather, the mobile device communicates with gaming devices 104A-104X and 200 using another wireless connection (e.g., WiFi® or cellular network). In another implementation, a wireless transceiver establishes a secure connection to directly communicate with the mobile device. The mobile device and gaming device 104A-104X and 200 sends and receives data utilizing the wireless transceiver instead of utilizing an external network. For example, the mobile device would perform digital wallet transactions by directly communicating with the wireless transceiver. In one or more implementations, a wireless transmitter could broadcast data received by one or more mobile devices without establishing a pairing connection with the mobile devices.

Although FIGS. 1 and 2A illustrate specific implementations of a gaming device (e.g., gaming devices 104A-104X and 200), the disclosure is not limited to those implementations shown in FIGS. 1 and 2. For example, not all gaming devices suitable for implementing implementations of the present disclosure necessarily include top wheels, top boxes, information panels, cashless ticket systems, and/or player tracking systems. Further, some suitable gaming devices have only a single game display that includes only a mechanical set of reels and/or a video display, while others are designed for bar counters or tabletops and have displays that face upwards. Gaming devices 104A-104X and 200 may also include other processors that are not separately shown. Using FIG. 2A as an example, gaming device 200 could include display controllers (not shown in FIG. 2A) configured to receive video input signals or instructions to display images on game displays 240 and 242. Alternatively, such display controllers may be integrated into the game

controller 202. The use and discussion of FIGS. 1 and 2 are examples to facilitate ease of description and explanation.

II.D. Example Gaming Environment

FIG. 2B depicts a casino gaming environment according to one example. In this example, the casino 251 includes banks 252 of EGMs 104. In this example, each bank 252 of EGMs 104 includes a corresponding gaming signage system 254 (also shown in FIG. 2A). According to this implementation, the casino 251 also includes mobile gaming devices 256, which are also configured to present wagering games in this example. The mobile gaming devices 256 may, for example, include tablet devices, cellular phones, smart phones and/or other handheld devices. In this example, the mobile gaming devices 256 are configured for communication with one or more other devices in the casino 251, including but not limited to one or more of the server computers 102, via wireless access points 258. In other examples, the mobile gaming devices 256 may also be configured for communication with one or more other devices external to the casino 251, e.g., players located elsewhere in a particular city, elsewhere in a particular state, at a particular casino's other locations, and so forth.

According to some examples, the mobile gaming devices 256 may be configured for stand-alone determination of game outcomes. However, in some alternative implementations the mobile gaming devices 256 may be configured to receive game outcomes from another device, such as the outcome determination server 106, one of the EGMs 104, etc.

Some mobile gaming devices 256 may be configured to accept monetary credits from a credit or debit card, via a wireless interface (e.g., via a wireless payment app), via tickets, via a patron casino account, etc. However, some mobile gaming devices 256 may not be configured to accept monetary credits via a credit or debit card. Some mobile gaming devices 256 may include a ticket reader and/or a ticket printer whereas some mobile gaming devices 256 may not, depending on the particular implementation.

In some implementations, the casino 251 may include one or more kiosks 260 that are configured to facilitate monetary transactions involving the mobile gaming devices 256, which may include cash out and/or cash in transactions. The kiosks 260 may be configured for wired and/or wireless communication with the mobile gaming devices 256. The kiosks 260 may be configured to accept monetary credits from casino patrons 262 and/or to dispense monetary credits to casino patrons 262 via cash, a credit or debit card, via a wireless interface (e.g., via a wireless payment app), via tickets, etc. According to some examples, the kiosks 260 may be configured to accept monetary credits from a casino patron and to provide a corresponding amount of monetary credits to a mobile gaming device 256 for wagering purposes, e.g., via a wireless link such as a near-field communications link. In some such examples, when a casino patron 262 is ready to cash out, the casino patron 262 may select a cash out option provided by a mobile gaming device 256, which may include a real button or a virtual button (e.g., a button provided via a graphical user interface) in some instances. In some such examples, the mobile gaming device 256 may send a "cash out" signal to a kiosk 260 via a wireless link in response to receiving a "cash out" indication from a casino patron. The kiosk 260 may provide monetary credits to the casino patron 262 corresponding to the "cash out" signal, which may be in the form of cash, a credit ticket, a credit transmitted to a financial account corresponding to the casino patron, etc.

In some implementations, a cash-in process and/or a cash-out process may be facilitated by the TITO system server 108. For example, the TITO system server 108 may control, or at least authorize, ticket-in and ticket-out transactions that involve a mobile gaming device 256 and/or a kiosk 260.

Some mobile gaming devices 256 may be configured for receiving and/or transmitting player loyalty information. For example, some mobile gaming devices 256 may be configured for wireless communication with the player tracking system server 110. Some mobile gaming devices 256 may be configured for receiving and/or transmitting player loyalty information via wireless communication with a patron's player loyalty card, a patron's smartphone, etc.

According to some implementations, a mobile gaming device 256 may be configured to provide safeguards that prevent the mobile gaming device 256 from being used by an unauthorized person. For example, some mobile gaming devices 256 may include one or more biometric sensors and may be configured to receive input via the biometric sensor(s) to verify the identity of an authorized patron. Some mobile gaming devices 256 may be configured to function only within a predetermined or configurable area, such as a casino gaming area. As will be described in further detail below, some mobile gaming devices 256 may be configured to play games in Social, Demo, or otherwise "Free-to-Play" modes that do not involve the wagering of real money.

II.E. Example Distributed Gaming Delivery

FIG. 2C is a diagram that shows examples of components of a system for providing online gaming according to some aspects of the present disclosure. As with other figures presented in this disclosure, the numbers, types and arrangements of gaming devices shown in FIG. 2C are merely shown by way of example. In this example, various gaming devices, including but not limited to end user devices (EUDs) 264a, 264b and 264c are capable of communication via one or more networks 417. The networks 417 may, for example, include one or more cellular telephone networks, the Internet, etc. In this example, the EUDs 264a and 264b are mobile devices: according to this example the EUD 264a is a tablet device and the EUD 264b is a smart phone. In this implementation, the EUD 264c is a laptop computer that is located within a residence 266 at the time depicted in FIG. 2C. Accordingly, in this example the hardware of EUDs is not specifically configured for online gaming, although each EUD is configured with software for online gaming. For example, each EUD may be configured with a web browser. Other implementations may include other types of EUD, some of which may be specifically configured for online gaming.

In this example, a gaming data center 276 includes various devices that are configured to provide online wagering games via the networks 417. The gaming data center 276 is capable of communication with the networks 417 via the gateway 272, including and one or more workstations 286a. In this example, switches 278 and routers 280 are configured to provide network connectivity for devices of the gaming data center 276, including storage devices 282a, servers 284a and one or more workstations 570a. The servers 284a may, for example, be configured to provide access to a library of games for online game play. In some examples, code for executing at least some of the games may initially be stored on one or more of the storage devices 282a. The code may be subsequently loaded onto a server 284a after selection by a player via an EUD and communication of that selection from the EUD via the networks 417. The server 284a onto which code for the selected game has been loaded

may provide the game according to selections made by a player and indicated via the player's EUD. In other examples, code for executing at least some of the games may initially be stored on one or more of the servers 284a. Although only one gaming data center 276 is shown in FIG. 2C, some implementations may include multiple gaming data centers 276.

In this example, a financial institution data center 270 is also configured for communication via the networks 417. Here, the financial institution data center 270 includes servers 284b, storage devices 282b, and one or more workstations 286b. According to this example, the financial institution data center 270 is configured to maintain financial accounts, such as checking accounts, savings accounts, loan accounts, etc. In some implementations one or more of the authorized users 274a-274c may maintain at least one financial account with the financial institution that is serviced via the financial institution data center 270.

According to some implementations, the gaming data center 276 may be configured to provide online wagering games in which money may be won or lost. According to some such implementations, one or more of the servers 284a may be configured to monitor player credit balances, which may be expressed in game credits, in currency units, or in any other appropriate manner. In some implementations, the server(s) 284a may be configured to obtain financial credits from and/or provide financial credits to one or more financial institutions, according to a player's "cash in" selections, wagering game results and a player's "cash out" instructions. According to some such implementations, the server(s) 284a may be configured to electronically credit or debit the account of a player that is maintained by a financial institution, e.g., an account that is maintained via the financial institution data center 270. The server(s) 284a may, in some examples, be configured to maintain an audit record of such transactions.

In some alternative implementations, the gaming data center 276 may be configured to provide online wagering games for which credits may not be exchanged for cash or the equivalent. In some such examples, players may purchase game credits for online game play, but may not "cash out" for monetary credit after a gaming session. Moreover, although the financial institution data center 270 and the gaming data center 276 include their own servers and storage devices in this example, in some examples the financial institution data center 270 and/or the gaming data center 276 may use offsite "cloud-based" servers and/or storage devices. In some alternative examples, the financial institution data center 270 and/or the gaming data center 276 may rely entirely on cloud-based servers. In still other examples, one or more third party cloud-based service providers may be utilized by a given casino, a given game developer, or given game studio to host backend game functionality for a number of different games (and/or a number of different players) simultaneously, according to a general service architecture and flexible backend platform design implementing a GDK to enhance and componentize game development.

One or more types of devices in the gaming data center 276 (or elsewhere) may be capable of executing middleware, e.g., for data management and/or device communication. Authentication information, player tracking information, etc., including but not limited to information obtained by EUDs 264 and/or other information regarding authorized users of EUDs 264 (including but not limited to the authorized users 274a-274c), may be stored on storage devices 282 and/or servers 284. Other game-related information

and/or software, such as information and/or software relating to leaderboards, players currently playing a game, game themes, game-related promotions, game competitions, etc., also may be stored on storage devices 282 and/or servers 284. In some implementations, some such game-related software may be available as "apps" and may be downloadable (e.g., from the gaming data center 276) by authorized users.

In some examples, authorized users and/or entities (such as representatives of gaming regulatory authorities) may obtain gaming-related information via the gaming data center 276. One or more other devices (such EUDs 264 or devices of the gaming data center 276) may act as intermediaries for such data feeds. Such devices may, for example, be capable of applying data filtering algorithms, executing data summary and/or analysis software, etc. In some implementations, data filtering, summary and/or analysis software may be available as "apps" and downloadable by authorized users.

II.F. Example Game Processing Architecture

FIG. 3 illustrates, in block diagram form, an implementation of a traditional, i.e., non-hosted, game processing architecture 300 that implements a game processing pipeline for the play of a game in accordance with various implementations described herein. As shown in FIG. 3, the gaming processing pipeline starts with having a UI system 302 receive one or more player inputs for the game instance. Based on the player input(s), the UI system 302 generates and sends one or more RNG calls to a game processing backend system 314. Game processing backend system 314 then processes the RNG calls with RNG engine 316 to generate one or more RNG outcomes. The RNG outcomes are then sent to the RNG conversion engine 320 to generate one or more game outcomes for the UI system 302 to display to a player. The game processing architecture 300 can implement the game processing pipeline using a gaming device, such as gaming devices 104A-104X and 200 shown in FIGS. 1 and 2, respectively. Alternatively, as will be discussed in further detail below, portions of the gaming processing architecture 300 can implement the game processing pipeline using a gaming device and one or more remote gaming devices, such as outcome determination server 106 shown in FIG. 1. In such implementations, the game processing pipeline may also utilize one or more game service clients, e.g., to pass inputs and requests between the gaming device/gaming application and the backend gaming system server that is hosting aspects of the game's functionality.

The UI system 302 includes one or more UIs that a player can interact with. The UI system 302 could include one or more game play UIs 304, one or more bonus game play UIs 308, and one or more multiplayer UIs 312, where each UI type includes one or more mechanical UIs and/or graphical UIs (GUIs). In other words, game play UI 304, bonus game play UI 308, and the multiplayer UI 312 may utilize a variety of UI elements, such as mechanical UI elements (e.g., physical "spin" button or mechanical reels) and/or GUI elements (e.g., virtual reels shown on a video display or a virtual button deck) to receive player inputs and/or present game play to a player. Using FIG. 3 as an example, the different UI elements are shown as game play UI elements 306A-306N and bonus game play UI elements 310A-310N.

The game play UI 304 represents a UI that a player typically interfaces with for a base game. During a game instance of a base game, the game play UI elements 306A-306N (e.g., GUI elements depicting one or more virtual reels) are shown and/or made available to a user. In a

subsequent game instance, the UI system 302 could transition out of the base game to one or more bonus games. The bonus game play UI 308 represents a UI that utilizes bonus game play UI elements 310A-310N for a player to interact with and/or view during a bonus game. In one or more implementations, at least some of the game play UI element 306A-306N are similar to the bonus game play UI elements 310A-310N. In other implementations, the game play UI element 306A-306N can differ from the bonus game play UI elements 310A-310N.

FIG. 3 also illustrates that UI system 302 could include a multiplayer UI 312 purposed for game play that differs or is separate from the typical base game. For example, multiplayer UI 312 could be set up to receive player inputs and/or presents game play information relating to a tournament mode. When a gaming device transitions from a primary game mode that presents the base game to a tournament mode, a single gaming device is linked and synchronized to other gaming devices to generate a tournament outcome. For example, multiple RNG engines 316 corresponding to each gaming device could be collectively linked to determine a tournament outcome. To enhance a player's gaming experience, tournament mode can modify and synchronize sound, music, reel spin speed, and/or other operations of the gaming devices according to the tournament game play. After tournament game play ends, operators can switch back the gaming device from tournament mode to a primary game mode to present the base game. Although FIG. 3 does not explicitly depict that multiplayer UI 312 includes UI elements, multiplayer UI 312 could also include one or more multiplayer UI elements.

Based on the player inputs, the UI system 302 could generate RNG calls to a game processing backend system 314. As an example, the UI system 302 could use one or more application programming interfaces (APIs) to generate the RNG calls. To process the RNG calls, the RNG engine 316 could utilize gaming RNG 318 and/or non-gaming RNGs 319A-319N. Gaming RNG 318 could correspond to RNG 212 or hardware RNG 244 shown in FIG. 2A. As previously discussed with reference to FIG. 2A, gaming RNG 318 often performs specialized and non-generic operations that comply with regulatory and/or game requirements. For example, because of regulation requirements, gaming RNG 318 could correspond to RNG 212 by being a cryptographic RNG or pseudorandom number generator (PRNG) (e.g., Fortuna PRNG) that securely produces random numbers for one or more game features. To securely generate random numbers, gaming RNG 318 could collect random data from various sources of entropy, such as from an operating system (OS) and/or a hardware RNG (e.g., hardware RNG 244 shown in FIG. 2A). Alternatively, non-gaming RNGs 319A-319N may not be cryptographically secure and/or be computationally less expensive. Non-gaming RNGs 319A-319N can, thus, be used to generate outcomes for non-gaming purposes. As an example, non-gaming RNGs 319A-319N can generate random numbers for generating random messages that appear on the gaming device.

The RNG conversion engine 320 processes each RNG outcome from RNG engine 316 and converts the RNG outcome to a UI outcome that is feedback to the UI system 302. With reference to FIG. 2A, RNG conversion engine 320 corresponds to RNG conversion engine 210 used for game play. As previously described, RNG conversion engine 320 translates the RNG outcome from the RNG 212 to a game outcome presented to a player. RNG conversion engine 320 utilizes one or more lookup tables 322A-322N to regulate a

prize payout amount for each RNG outcome and how often the gaming device pays out the derived prize payout amounts. In one example, the RNG conversion engine 320 could utilize one lookup table to map the RNG outcome to a game outcome displayed to a player and a second lookup table as a pay table for determining the prize payout amount for each game outcome. In this example, the mapping between the RNG outcome and the game outcome controls the frequency in hitting certain prize payout amounts. Different lookup tables could be utilized depending on the different game modes, for example, a base game versus a bonus game.

After generating the UI outcome, the game processing backend system 314 sends the UI outcome to the UI system 302. (As mentioned above, in embodiments wherein aspects of the game's functionality are hosted by a backend server, the UI outcomes may be determined by the hosted game backend and then returned to the game via an application service layer so that the game application may update the appropriate audio and/or visual gameplay elements.) Examples of UI outcomes are symbols to display on a video reel or reel stops for a mechanical reel. In one example, if the UI outcome is for a base game, the UI system 302 updates one or more game play UI elements 306A-306N, such as symbols, for the game play UI 304. In another example, if the UI outcome is for a bonus game, the UI system could update one or more bonus game play UI elements 310A-310N (e.g., symbols) for the bonus game play UI 308. In response to updating the appropriate UI, the player may subsequently provide additional player inputs to initiate a subsequent game instance that progresses through the game processing pipeline.

III. Example Embodiments

III.A. Exemplary Hosted Gaming Platform

According to some embodiments, a hosted gaming platform may be comprised of multiple servers and APIs, whose purpose is to expose the math and game logic of different games to different services, such as storage, player account management, and the game itself. One aim of the hosted gaming platform's architecture is to be able supply functionality to the game/application service client with horizontally-scalable services and the ability to operate across multiple platforms (e.g., Class-II gaming, Class-III gaming, real-money wagering, Social gaming, Demo-mode gaming, etc.), technology stacks, machines, interfaces, etc. According to some embodiments, the backend host platform can facilitate several different backends that are functionally separated and/or are physically distinct from one another.

According to some embodiments, the hosted gaming platform may comprise: one or more remote gaming servers (RGS); one or more mobile gaming platforms; and one or more individual game backend host systems. The role of remote gaming servers, according to some embodiments, may include routing incoming game requests, facilitating gaming session management, maintaining a ledger of gaming transactions, performing reconciliation of incomplete transactions, and reporting game outcomes (including regulatory reporting). The role of the mobile gaming platforms is to manage the gameplay and determine random-based game-play outcomes. Finally, the role of the game backends, according to some embodiments, is to encapsulate the business logic for a given service, including core concepts, such as a state machine, Par sheets, whether to show a dollar sign (or other currency sign) in front of a player's credit balance depending on whether the player is playing in a RMG mode

or a Social/Demo mode, and/or mathematical calculations needed for a given application/game.

According to some embodiments, the decision of where to route incoming gameplay requests from players may be made by the one or more RGSs, i.e., rather than a PAM system. In this way, the RGS is able to perform any desired analytics on incoming requests, and then route the requests to the appropriate portions of the platform infrastructure, e.g., to a first server(s) if the incoming request relates to a real-money gaming session, and/or via an interface to a second server(s) (e.g., a remote, cloud-based server) if the incoming request relates to a Social, Demo, or other form of Free-to-Play gaming session. Thus, in some embodiments, based on a flag or other parameter that is set in an incoming gaming request, the RGS may either serve the game from the current remote gaming instance setup, or it may be redirected to an instance hosted by an outside or third-party server. The PAM system can then reach out to the appropriate endpoint for the current gameplay session that it is managing.

III.B. An Improved Multi-Form Hosted Gaming Platform Architecture

Turning now to FIG. 4, an example of a multi-form hosted gaming platform architecture 400 is shown, in accordance with various implementations described herein. In particular, architecture 400 shows various Player Account Management (PAM) systems, which may, e.g., be operated by a particular casino or other provider. For example, PAM (RMG) Class-II 402 may be capable of managing player information for one or more Class-II RMG games, while PAM (Social) Class-II 404 may be capable of managing player information for one or more Class-II Social (or other “Free-to-Play” style) games. Similarly, PAM (RMG) Class-III 406 may be capable of managing player information for one or more Class-III RMG games, while PAM (Social) Class-III 408 may be capable of managing player information for one or more Class-III Social (or other “Free-to-Play” style) games.

According to some embodiments, depending on the type of game that a player is currently playing, the corresponding PAM may contact the “Social and RMG Remote Gaming Server” (426), which may comprise a remote gaming server (“RGS”) 418, as well as an RGS Content Integration module 420. The RGS 418 may comprise various “microservices,” or it could be implemented as a monolithic system able to switch between RMG and Social games. The RGS content integration module 420 may serve as the link between the game a player is playing (e.g., a Class-II game) and the RGS 418. By routing the incoming requests at the RGS 418 (i.e., rather than at the PAM itself), the Social and RMG remote game server 426 may be able to perform various analytics and analysis operations, e.g., regarding the numbers and volume of play on each game between RMG players and non-RMG (e.g., “Social” or “Demo”) players. In some embodiments, the Social and RMG remote game server 426 may also be configured to maintain a temporary “wallet” for players in Social, Demo, or other non-RMG modes, so that credits/debits may be made directly to the player’s temporary wallet during the non-RMG gameplay session, i.e., rather than repeatedly contacting and updated the player’s credit balance with an external PAM.

A game development kit (GDK) game host 422 may be used to render the game information that is to be sent to a frontend game UI 424 as may be running on a client device (e.g., a mobile device), and it may rely on mobile Class-II/Class-III platform 428 to generate the (often randomized) game outcomes. Every outcome may be linked with one

game server communicating with a particular game client (e.g., labeled as 424 in FIG. 1), and each game server may be capable of hosting hundreds or thousands of game instances at once.

For example, depending on whether a mobile Class-II or a mobile Class-III game is being played in a given embodiment, the mobile Class-II/Class-III platform 428 may comprise an outcome resolver 414, which may be used to determine outcomes across the various instances of mobile Class-II or mobile Class-III games being played at a given time. In the case of a Mobile Class-II Bingo game, there may be a Bingo Game Manager 412, which pings a Bingo Server 410 to determine the results and outcomes of each “ball call.” In the case of a RMG Class-II games, a physical bingo server may have to be located in the casino/gaming environment, whereas, for Social gaming, the server may be hosted in a cloud server instance. By contrast, in the case of a Mobile Class-III game, the outcome resolver 414 of the mobile Class-II/Class-III platform 428 may rely on a Random Number Generator (“RNG”) 416 to generate the game outcomes.

As may now be appreciated, some of the key features of the above-described multi-form gaming platform for online and social gaming may include: (1) the ability to use a single RGS for each of RMG, Social, and Demo game modes; (2) the ability to use Class-II games for social gaming; (3) the ability for a gaming platform to derive outcomes based on reel positions (which positions may be derived from the Bingo game for Class-II games and from an RNG for Class-III games); (4) the ability to allow game configurations to define the type of game (e.g., Class-II or Class-III) that will be played in a given gameplay session; and (5) the ability to have a parameter that may be set at the time of game launch to define a game mode (e.g., RMG/Demo/Social mode, etc.).

III.C. Exemplary Configurations for an Improved Multi-Form Hosted Gaming Platform Architecture

Turning now to FIG. 5A, an exemplary multi-form hosted gaming platform architecture configuration for mobile Class-II gaming 500 is shown, in accordance with various implementations described herein. As compared with FIG. 4 described above, the architecture configuration 500 shown in FIG. 5A is reflective of a mobile Class-II gaming session. Thus, the mobile Class-II/Class-III platform 428 from FIG. 4 has been replaced by mobile Class-II platform 502, which comprises only the outcome resolver 414 and the Bingo game manager 412, and the Class-III PAMs 406 and 408 are not shown. In other words, since the current gaming session is only involving Class-II, there are no calls needed to RNG 416 or to any Class-III PAMs.

As mentioned above, the mobile Class-II platform 502 server may comprise an outcome resolver 414. In the case of a mobile Class-II Bingo game, the Bingo game manager 412 may make a call to Bingo Server 410 to determine the results and outcomes of each “ball call.” In the case of a RMG Class-II games, a physical bingo server may have to be located in the casino/gaming environment (e.g., for regulatory reasons), whereas, for Social-non-RMG gaming, the bingo server 410 may be hosted in a cloud server instance and used to balance request loads across many different players and/or sites (as well as be flexibly updated to other cloud service providers as desired). Again, the RGS 418 may route incoming gameplay requests differently, based on whether an RMG or a non-RMG gameplay session has been launched, while still leveraging the same gaming platform.

Turning now to FIG. 5B, an exemplary multi-form hosted gaming platform architecture configuration for mobile

Class-III gaming **550** is shown, in accordance with various implementations described herein. As compared with FIG. 4 described above, the architecture configuration **550** shown in FIG. 5B is reflective of a mobile Class-III gaming session. Mobile Class-III gaming is more highly-regulated than mobile Class-II gaming, and includes typical casino-based games, such as slot machines, blackjack, craps, roulette, and any other game of chance. Thus, the mobile Class-II/Class-III platform **428** from FIG. 4 has been replaced by mobile Class-III platform **552**, which comprises only the outcome resolver **414** and the RNG **416** for determining and interpreting random-based generated game outcomes. In other words, Bingo Server **410**, Bingo game manager **412**, and the Class-II PAMs **402** and **404** are not shown. Because the current gaming session in this example is only involving Class-III, there are no calls needed to the Class-II/Bingo game portion of the infrastructure.

Also shown in FIG. 5B is another exemplary PAM, PAM (Demo) Class-III **554**, which may be capable of managing player information for one or more Class-III Demo games, where the Demo gameplay is effectively the same as “normal” RMG gameplay, but the same Class-III regulatory considerations do not necessarily apply, since no real money is being wagered when in Demo mode. Playing mobile Class-III games in non-RMG modes may also allow for incoming gameplay requests to be routed by the RGS **418**, via at least one interface, to a non-RMG infrastructure, which may be external to the RMG infrastructure, e.g., hosted by a third-party cloud-service provider.

III.D. Exemplary Methods for Executing Gameplay Requests in a Multi-Form Hosted Gaming Environment

Turning now to FIG. 6, a flowchart is shown, illustrating an example method **600** for performing an embodiment of the disclosed technology related to executing a flexible, multi-form hosted gaming platform architecture. First, at **602**, the method **600** may execute a hosted gaming platform, wherein the hosted gaming platform comprises at least a remote gaming server (RGS), a real money gaming (RMG) infrastructure (e.g., one or more servers, outcome resolvers, game managers, or the like that are configured to manage and determine gameplay outcomes involving real money wagers), and at least one interface to a non-RMG infrastructure. Next, at **604**, the method **600** may receive, at the RGS, a first request from a current round of a first gameplay session executing at a frontend gaming client, wherein the first request comprises at least session metadata and an identifier for a first user, wherein the session metadata indicates whether the first gameplay session comprises a RMG session or a non-RMG session.

Next, at **606**, the method **600** may, e.g., in response to the session metadata indicating that the first gameplay session comprises a RMG session, execute, using at least the RMG infrastructure, the first request to produce one or more results for the current round. At **608**, the method **600** may, e.g., in response to the session metadata indicating that the first gameplay session comprises a non-RMG session, route the first request, via the at least one interface, to the non-RMG infrastructure (which may, e.g., be deployed on a cloud server instance external to the RGS), and receive one or more results for the current round produced by the non-RMG infrastructure. Finally, at **610**, the method **600** may return the one or more results for the current round to the frontend gaming client.

Turning now to FIG. 7, a process flow diagram **700** is shown, illustrating additional details regarding an example method for performing an embodiment of the disclosed technology related to executing a flexible, multi-form hosted

gaming platform architecture for a game operating in a “Demo” mode. First, at **712**, a gameplay session may be launched by a player (e.g., from Lobby **702**) with a Demo mode type, e.g., a free-to-play game mode that does not involve the wagering of real money. The game launch request may be received at Launcher **704** and, if indeed the current gameplay session has been launched with a Demo mode type, the functionality of box **714** may be performed.

First, at **716**, the Launcher may create a game session ID (or other form of session metadata). Next, at **718**, the Remote Gaming Platform (RGP) **706** may make an offline session call to Remote Content Integration (RCI) **708**. As discussed above, the RGP may, among other things, serve the roles of: a) managing the gaming sessions; b) keeping transaction records; and c) routing incoming requests to a GDK or other third party RGS systems. According to some embodiments, RCI **708** is an intermediate application that manages the different game classes (e.g., Class-II or Class-III) and may also work as the request/response translator between the RGP and a GDK or other third party RGS. In the case of a Class-II system, this application may also serve as the intermediary between the Bingo game and GDK. Thus, at RCI **708**, if the current gameplay session has been launched with a Demo mode type, the functionality of box **720** may be performed, i.e., the RCI **708** may generate necessary configuration parameters and add the Demo game type designation to the current gameplay session. At **722**, the configuration parameters may be returned to RGP **706**, and ultimately returned to Launcher **704** at **724**, wherein at **726**, the Launcher **704** may launch the current gameplay session in the Demo mode.

Next, at **728**, Launcher **704** may request the game frontend content and pass the configuration parameters to the game host **710**. At **730**, the game host **710** may return the game frontend content so that the Launcher **704** may launch the gameplay session. During gameplay, the Launcher **704** may also, from time-to-time, request different files to be loaded from the game host **710** (**732**), and then receive the requested files from the game host **710** (**734**), such that the player may receive the requested gameplay experience. As may now be appreciated, because the game session was launched in a Demo mode, the player’s credit balance may be maintained in a temporary wallet or other data structure at the RGS, and there does not need to be any credits/deductions applied to the player’s balance amount at a PAM with each spin/round of game play, thereby saving additional resources and bandwidth. Moreover, utilizing a Demo mode allows the RGP to perform adaptive routing, e.g., load-based routing, as well as rich data analytics across multiple types of gameplay using a single server instance.

IV. Alternatives, Variations, and Conclusion

Numerous embodiments are described in this disclosure and are presented for illustrative purposes only. The described embodiments are not, and are not intended to be, limiting in any sense. The present disclosure is widely applicable to numerous embodiments, as is readily apparent from the disclosure. One of ordinary skill in the art will recognize that the innovations described herein may be practiced with various modifications and alterations, such as structural, logical, software, and electrical modifications. Although particular features of the innovations described herein may be described with reference to one or more particular embodiments and/or drawings, it should be understood that such features are not limited to usage in the one

or more particular embodiments or drawings with reference to which they are described, unless expressly specified otherwise.

The present disclosure is neither a literal description of all embodiments nor a listing of features of the innovations described herein that must be present in all embodiments.

The Title (set forth at the beginning of the first page of this disclosure) is not to be taken as limiting in any way as the scope of the disclosed embodiments.

When an ordinal number (such as "first," "second," "third" and so on) is used as an adjective before a term, that ordinal number is used (unless expressly specified otherwise) merely to indicate a particular feature, such as to distinguish that particular feature from another feature that is described by the same term or by a similar term. For example, a "first widget" may be so named merely to distinguish it from, e.g., a "second widget." Thus, the mere usage of the ordinal numbers "first" and "second" before the term "widget" does not indicate any other relationship between the two widgets, and likewise does not indicate any other characteristics of either or both widgets. For example, the mere usage of the ordinal numbers "first" and "second" before the term "widget" (1) does not indicate that either widget comes before or after any other in order or location; (2) does not indicate that either widget occurs or acts before or after any other in time; and (3) does not indicate that either widget ranks above or below any other, as in importance or quality. In addition, the mere usage of ordinal numbers does not define a numerical limit to the features identified with the ordinal numbers. For example, the mere usage of the ordinal numbers "first" and "second" before the term "widget" does not indicate that there must be no more than two widgets.

When introducing elements of aspects of the present disclosure or embodiments thereof, the articles "a," "an," "the," and "said" are intended to mean that there are one or more of the elements. The terms "comprising," "including," and "having" are intended to be inclusive and mean that there may be additional elements other than the listed elements.

When a single device, component, structure, or article is described herein, more than one device, component, structure or article (whether or not they cooperate) may alternatively be used in place of the single device, component or article that is described. Accordingly, the functionality that is described as being possessed by a device may alternatively be possessed by more than one device, component or article (whether or not they cooperate).

Similarly, where more than one device, component, structure, or article is described herein (whether or not they cooperate), a single device, component, structure, or article may alternatively be used in place of the more than one device, component, structure, or article that is described. For example, a plurality of computer-based devices may be substituted with a single computer-based device. Accordingly, the various functionality that is described as being possessed by more than one device, component, structure, or article may alternatively be possessed by a single device, component, structure, or article.

The functionality and/or the features of a single device that is described may be alternatively embodied by one or more other devices that are described but are not explicitly described as having such functionality and/or features. Thus, other embodiments need not include the described device itself, but rather can include the one or more other devices which would, in those other embodiments, have such functionality/features.

Further, the systems and methods described herein are not limited to the specific embodiments described herein but, rather, operations of the methods and/or components of the system and/or apparatus may be utilized independently and separately from other operations and/or components described herein. Further, the described operations and/or components may also be defined in, or used in combination with, other systems, methods, and/or apparatus, and are not limited to practice with only the systems, methods, and storage media as described herein.

Devices that are in communication with each other need not be in continuous communication with each other, unless expressly specified otherwise. On the contrary, such devices need only transmit to each other as necessary or desirable, and may actually refrain from exchanging data most of the time. For example, a machine in communication with another machine via the Internet may not transmit data to the other machine for weeks at a time. In addition, devices that are in communication with each other may communicate directly or indirectly through one or more intermediaries.

A description of an embodiment with several components or features does not imply that all or even any of such components and/or features are required. On the contrary, a variety of optional components are described to illustrate the wide variety of possible embodiments of the innovations described herein. Unless otherwise specified explicitly, no component and/or feature is essential or required.

Further, although process steps, algorithms or the like may be described in a sequential order, such processes may be configured to work in different orders. In other words, any sequence or order of steps that may be explicitly described does not necessarily indicate a requirement that the steps be performed in that order. The steps of processes described herein may be performed in any order practical. Further, some steps may be performed simultaneously despite being described or implied as occurring non-simultaneously (e.g., because one step is described after the other step). Moreover, the illustration of a process by its depiction in a drawing does not imply that the illustrated process is exclusive of other variations and modifications thereto, does not imply that the illustrated process or any of its steps are necessary to the innovations described herein, and does not imply that the illustrated process is preferred.

Although a process may be described as including a plurality of steps, that does not indicate that all or even any of the steps are essential or required. Various other embodiments within the scope of the present disclosure include other processes that omit some or all of the described steps. Unless otherwise specified explicitly, no step is essential or required.

Although a product may be described as including a plurality of components, aspects, qualities, characteristics and/or features, that does not indicate that all of the plurality are essential or required. Various other embodiments within the scope of the present disclosure include other products that omit some or all of the described plurality.

An enumerated list of items (which may or may not be numbered) does not imply that any or all of the items are mutually exclusive, unless expressly specified otherwise. Likewise, an enumerated list of items (which may or may not be numbered) does not imply that any or all of the items are comprehensive of any category, unless expressly specified otherwise. For example, the enumerated list "a computer, a laptop, a PDA" does not imply that any or all of the three items of that list are mutually exclusive and does not imply that any or all of the three items of that list are comprehensive of any category.

Headings of sections provided in this disclosure are for convenience only, and are not to be taken as limiting the disclosure in any way.

For the sake of presentation, the detailed description uses terms like "determine" and "select" to describe computer operations in a computer system. These terms denote operations performed by a computer, and should not be confused with acts performed by a human being. The actual computer operations corresponding to these terms vary depending on implementation. For example, "determining" something can be performed in a variety of manners, and therefore the term "determining" (and like terms) can indicate calculating, computing, deriving, looking up (e.g., in a table, database or data structure), ascertaining, recognizing, and the like.

As used herein, the term "send" denotes any way of conveying information from one component to another component, and the term "receive" denotes any way of getting information at one component from another component. The two components can be part of the same computer system or different computer systems. The information can be passed by value (e.g., as a parameter of a message or function call) or passed by reference (e.g., in a buffer). Depending on context, the information can be communicated directly between the two components or be conveyed through one or more intermediate components. As used herein, the term "connected" denotes an operable communication link between two components, which can be part of the same computer system or different computer systems. The operable communication link can be a wired or wireless network connection, which can be direct or pass through one or more intermediate components (e.g., of a network). Communication among computers and devices may be encrypted to insure privacy and prevent fraud in any of a variety of ways well known in the art.

It will be readily apparent that the various methods and algorithms described herein may be implemented by, e.g., appropriately programmed general-purpose computers and computing devices. Typically a processor (e.g., one or more microprocessors) will receive instructions from a memory or like device, and execute those instructions, thereby performing one or more processes defined by those instructions. Further, programs that implement such methods and algorithms may be stored and transmitted using a variety of media (e.g., computer readable media) in a number of 45 manners. In some embodiments, hard-wired circuitry or custom hardware may be used in place of, or in combination with, software instructions for implementation of the processes of various embodiments. Thus, embodiments are not limited to any specific combination of hardware and software. Accordingly, a description of a process likewise describes at least one apparatus for performing the process, and likewise describes at least one computer-readable medium for performing the process. The apparatus that performs the process can include components and devices (e.g., a processor, input and output devices) appropriate to 50 perform the process. A computer-readable medium can store program elements appropriate to perform the method.

The term "computer-readable medium" refers to any non-transitory storage or memory that may store computer-executable instructions or other data in a computer system and be read by a processor in the computer system. A computer-readable medium may take many forms, including but not limited to non-volatile storage or memory (such as optical or magnetic disk media, a solid-state drive, a flash drive, PROM, EPROM, and other persistent memory) and volatile memory (such as DRAM). The term "computer-

readable media" excludes signals, waves, and wave forms or other intangible or transitory media that may nevertheless be readable by a computer.

The present disclosure provides, to one of ordinary skill in the art, an enabling description of several embodiments and/or innovations. Some of these embodiments and/or innovations may not be claimed in the present application, but they may nevertheless be claimed in one or more continuing applications that claim the benefit of priority of 10 the present application. Applicants may file additional applications to pursue patents for subject matter that has been disclosed and enabled but not claimed in the present application.

The foregoing description discloses only exemplary 15 embodiments of the present disclosure. Modifications of the above disclosed apparatus and methods which fall within the scope of the present disclosure will be readily apparent to those of ordinary skill in the art. For example, although the examples discussed above are illustrated for a gaming 20 market, embodiments of the present disclosure can be implemented for other markets. The gaming system environment of the examples is not intended to suggest any limitation as to the scope of use or functionality of any aspect of the disclosure.

25 In view of the many possible embodiments to which the principles of the disclosed invention may be applied, it should be recognized that the illustrated embodiments are only preferred examples of the invention and should not be taken as limiting the scope of the invention. Rather, the scope of the invention is defined by the following claims. We 30 therefore claim as our invention all that comes within the scope and spirit of these claims.

While the disclosure has been described with respect to the figures, it will be appreciated that many modifications 35 and changes may be made by those skilled in the art without departing from the spirit of the disclosure. Any variation and derivation from the above description and figures are included in the scope of the present disclosure as defined by the claims.

40 What is claimed is:

1. A system, comprising:
one or more processors;
memory; and
control logic, implemented using the one or more processors and the memory, and configured to perform operations, comprising:
executing a hosted gaming platform, wherein the hosted gaming platform comprises at least a remote gaming server (RGS) instance, a real money gaming (RMG) infrastructure, and at least one interface to a non-RMG infrastructure, wherein the non-RMG infrastructure is hosted by a server external to the RMG infrastructure;
receiving, at the RGS instance, a first request from a current round of a first gameplay session executing at a frontend gaming client, wherein the first request comprises at least session metadata and an identifier for a first user, and wherein the session metadata indicates whether the first gameplay session comprises an RMG session or a non-RMG session;
in response to the session metadata indicating that the first gameplay session comprises an RMG session:
routing the first request for execution using at least the RMG infrastructure, wherein execution of the first request produces one or more results for the current round; and

returning the one or more produced results for the current round to the frontend gaming client; and in response to the session metadata indicating that the first gameplay session comprises a non-RMG session:

- routing the first request, via the at least one interface, to the non-RMG infrastructure hosted by the server external to the RMG infrastructure;
- receiving one or more results for the current round produced by the non-RMG infrastructure; and
- returning the one or more received results for the current round to the frontend gaming client.

2. The system of claim 1, wherein the RGS is configured to manage one or more user wallets.

3. The system of claim 2, wherein the one or more wallets comprise: at least one RMG wallet; and at least one non-RMG wallet.

4. The system of claim 1, wherein the RGS is configured to receive information from: one or more external Class-II player account management (PAM) systems; and one or more external Class-III PAM systems.

5. The system of claim 1, wherein the first gameplay session comprises at least one of: a Class-II gameplay session; or a Class-III gameplay session.

6. The system of claim 5, wherein, for Class-II gameplay sessions, producing the one or more results further comprises: utilizing a bingo server.

7. The system of claim 5, wherein, for Class-III gameplay sessions, producing the one or more results further comprises: utilizing an outcome resolver and a random number generator (RNG).

8. The system of claim 1, wherein the non-RMG infrastructure comprises: an infrastructure configured to produce results for Social gameplay sessions; or an infrastructure configured to produce results for Demo gameplay sessions.

9. One or more computer-readable media storing computer-executable instructions, which, when executed by a computer, cause the computer to perform the following operations:

- execute a hosted gaming platform, wherein the hosted gaming platform comprises at least a remote gaming server (RGS) instance, a real money gaming (RMG) infrastructure, and at least one interface to a non-RMG infrastructure, wherein the non-RMG infrastructure is hosted by a server external to the RMG infrastructure;
- receive, at the RGS instance, a first request from a current round of a first gameplay session executing at a frontend gaming client, wherein the first request comprises at least session metadata and an identifier for a first user, and wherein the session metadata indicates whether the first gameplay session comprises an RMG session or a non-RMG session;
- in response to the session metadata indicating that the first gameplay session comprises an RMG session:

  - route the first request for execution, using at least the RMG infrastructure, wherein execution of the first request produces one or more results for the current round; and
  - return the one or more produced results for the current round to the frontend gaming client; and

- in response to the session metadata indicating that the first gameplay session comprises a non-RMG session:

  - route the first request, via the at least one interface, to the non-RMG infrastructure hosted by the server external to the RMG infrastructure;
  - receive one or more results for the current round produced by the non-RMG infrastructure; and

return the one or more received results for the current round to the frontend gaming client.

10. The one or more computer-readable media of claim 9, wherein the RGS is configured to manage one or more user wallets.

11. The one or more computer-readable media of claim 9, wherein the RGS is configured to receive information from: one or more external Class-II player account management (PAM) systems; and one or more external Class-III PAM systems.

12. The one or more computer-readable media of claim 9, wherein the first gameplay session comprises at least one of: a Class-II gameplay session; or a Class-III gameplay session.

13. The one or more computer-readable media of claim 12, wherein for Class-II gameplay sessions, producing the one or more results further comprises: utilizing a bingo server.

14. The one or more computer-readable media of claim 12, wherein, for Class-III gameplay sessions, producing the one or more results further comprises: utilizing an outcome resolver and a random number generator (RNG).

15. The one or more computer-readable media of claim 9, wherein the non-RMG infrastructure comprises: an infrastructure configured to produce results for Social gameplay sessions; or an infrastructure configured to produce results for Demo gameplay sessions.

16. A computer-implemented method, comprising:

- executing a hosted gaming platform, wherein the hosted gaming platform comprises at least a remote gaming server (RGS) instance, a real money gaming (RMG) infrastructure, and at least one interface to a non-RMG infrastructure, wherein the non-RMG infrastructure is hosted by a server external to the RMG infrastructure;
- receiving, at the RGS instance, a first request from a current round of a first gameplay session executing at a frontend gaming client, wherein the first request comprises at least session metadata and an identifier for a first user, and wherein the session metadata indicates whether the first gameplay session comprises an RMG session or a non-RMG session;
- in response to the session metadata indicating that the first gameplay session comprises an RMG session:

  - routing the first request for execution, using at least the RMG infrastructure, wherein the execution of the first request produces one or more results for the current round; and
  - returning the one or more produced results for the current round to the frontend gaming client; and

- in response to the session metadata indicating that the first gameplay session comprises a non-RMG session:

  - routing the first request, via the at least one interface, to the non-RMG infrastructure hosted by the server external to the RMG infrastructure;
  - receiving one or more results for the current round produced by the non-RMG infrastructure; and
  - returning the one or more received results for the current round to the frontend gaming client.

17. The computer-implemented method of claim 16, wherein the RGS is configured to receive information from: one or more external Class-II player account management (PAM) systems; and one or more external Class-III PAM systems.

18. The computer-implemented method of claim 16, wherein the first gameplay session comprises at least one of: a Class-II gameplay session; or a Class-III gameplay session.

19. The computer-implemented method of claim 18, wherein for Class-II gameplay sessions, producing the one or more results further comprises: utilizing a bingo server.

20. The computer-implemented method of claim 18, wherein, for Class-III gameplay sessions, producing the one or more results further comprises: utilizing an outcome resolver and a random number generator (RNG). 5
